SASH BALANCE

Ward P. Kessler, near Bristol, Ind., assignor to
Victor M. Langsett, Chicago, Ill., as trustee

Application July 29, 1947, Serial No. 764,402

6 Claims. (Cl. 189—72)

1

In double hung sash, it is common practice to use counter-balances to offset the weight of the sash, and where spring balances are used, they are generally applied or installed without the perimeter of the window frame, for example, resting on the top member of the frame. This requires special treatment of the adjoining wall construction to accommodate the balances, and makes access difficult after installation of the window has been completed. My invention relates to improved methods of installing a spring balance within the perimeter of the window frame, where the upper sash is fixed, directly over the sash track, resulting in reduction of friction and wear upon the balance tape, permitting ready access for repair or replacement, and making special treatment of the adjoining wall construction unnecessary. The window frame and sash are preferably made of formed metal or metal alloy by extrusion.

Further objects and advantages of the invention will be apparent from the following specification and the accompanying drawings, wherein a preferred embodiment of the invention has been shown and described.

In the drawings:

Figure 1 is a perspective view of the inner, upper-right hand corner of a formed metal window frame, with fixed upper sash, showing the spring balance in position and the face strip and sash guide and movable lower sash shown in part only.

Figure 2 is a side view of a portion of the face strip and sash guide showing the sash guide cut away to accommodate the balance.

Figure 3 is a perspective view of a cover plate used as another means of holding the balance in position.

The complete window has not been shown in the drawings, but from common knowledge and as indicated by the drawings, it is obvious that it consists of a frame, a fixed upper sash, and a vertically movable double hung lower sash.

Similar numerals refer to similar parts throughout the several views.

Referring to Figure 1 of the drawings, a formed main frame 1 with a plurality of angularly disposed walls, hereinafter called frame surfaces, including the frame surfaces 2, 3, 4, 5, 6, 7, 8 and 9, a plurality of obstructions, including the obstructions 10, 11, 12 and 13, and a plurality of channels, both L and U-shaped, including the L-shaped channels 14 and 15, is fabricated, preferably of extruded aluminum. The side and top members of the frame are joined at the corners, as at 22, by mechanical means, brazing or other suitable means. The glass 16 in the fixed upper sash formed by the main frame, abuts against the obstructions 10 and

11 on the frame surface 6 and obstructions 12 and

13 on the frame surface 7, and is held in place and weather proofed by the putty 17. A portion of the frame surface 4 is removed commencing with its end contacting the frame surface 3 for a distance substantially equal to the height of the balance, as shown at 18, forming the recess 19. A standard spring balance 20 is inserted into this recess 19, one end side 21 abutting against the inner face of the frame surface 8, its bottom side 23 resting on the end 24 of the frame surface 4 and its sides 25 and 26, abutting against the inner faces of the frame surfaces 6 and 2, respectively, the balance tape 27 being attached to the upper right hand corner of the movable lower sash 43, by any suitable means, such as the screw 34. The balance tape 27 is hidden from view by the face strip 28. This formed face strip 28 has an inturned leg 29 serving as a guide for the lower sash and the lip 30, which conforms to and abuts against the channel 14 and the side 31 abuts against the inner face of the frame surface 2, where it is held in position by a plurality of screws, for example, the screw 32, passing through the hole 33 in the frame surface 2 and engaging a threaded receiver. The balance tape 27 extends downwardly behind the face strip 28 and between it and the sash guide 29. This face strip 28 and sash guide 29 extend upwardly to the bottom 23 of the balance 20, which rests thereon. If desired, the face strip 28 may be continued upwardly, supporting and concealing the end side 35 of the balance 20 by removing a sufficient portion of the guide 29 at 36 as shown in Figure 2 to accommodate the said balance 20. I prefer to conceal and further support the balance in position by using the angular cover plate 37 shown in Figure 3. When this balance cover plate 37 is used, the face strip 28 ends at point 40 of contact therewith. The leg ends 38 and 39 of the cover plate 37 abut against the surfaces of the channels 14 and 15, respectively, in the frame 1 and said cover plate is held in position by the screws 32, 32, inserted through the holes 40, 40, therein and the holes 41, 42 in the frame surfaces 6 and 5, respectively, and engaging threaded receivers. By use of this cover plate 37, the balance is wholly concealed, and is readily accessible for replacement or repair without removing the face strip 28 and sash guide 29. It is also apparent that the balance 20 is contained, in part, in the recess 19, behind the glass 16 in the fixed upper sash and wholly within the perimeter of the window frame 1 and directly above the lower sash. While I have particularly described the invention in relation to the right upper hand balance application, it is obvious that similar application may be used in installing the upper left hand balance.

60 Also, while I have described in detail above the

application of the balance just below the upper frame surface 1, my invention may be used in installing the balances in similar positions in the upper sash below the position described in detail in order to shorten the length of the balance tape. For example, in windows having the greater part thereof in the form of a fixed upper sash with a movable lower sash of lesser height, I have found it to be an advantage to install the balance by means of my invention within the frame as described at a distance above and substantially equal to the height of the movable lower sash, thereby permitting a full vent opening upon raising the movable sash and reducing the length of the balance tape required to 15 suspend said sash.

Changes may be made in the form, construction and arrangement of the parts without departing from the spirit of the invention or sacrificing any of its advantages, and the right is hereby reserved to make all such changes as fairly fall within the scope of the following claims.

I claim as my invention:

1. A spring balance application in a window frame having a fixed upper sash and a vertically movable sash therebelow, comprising a formed main frame with vertical and horizontal members; a vertically movable lower sash; vertical side members of said main frame having a recess formed in each member thereof within the perimeter of said frame laterally of said fixed sash, below the upper horizontal frame member and above the movable lower sash; a spring balance removably positioned in each recess abutting 35 against the adjacent surfaces of said frame and resting upon said frame at the lower end of said recess; a balance tape depending from each balance laterally of said fixed sash and attached to said lower sash; and means removably secured to said main frame for retaining said balances in position.

2. A spring balance application in a window having a fixed upper sash and a vertically slideable sash therebelow, comprising a formed main frame with horizontal and vertical members; a lower sash vertically slideable within said main frame; vertical side members of said main frame having a recess within the perimeter of each member thereof laterally of said fixed sash, below the upper horizontal frame member and above said slideable lower sash; a spring balance removably positioned in each of said recesses and supported therein by close contact with the adjacent surfaces of said frame with its balance tape orifice directly over the said lower sash; and a balance tape depending from each balance laterally of said fixed sash and attached to said lower sash.

3. A window construction having a fixed upper sash and vertically slideable lower sash comprising a formed main frame with horizontal and vertical members; a vertically slideable lower sash; vertical side members of said main frame having recesses in each member thereof adjacent to and extending behind the frame surfaces thereof supporting the glass in the fixed upper sash, below the upper horizontal frame member and above said slideable lower sash, adapted to receive and support a spring balance in each of said recesses; a spring balance positioned in each recess abutting against the adjacent frame surfaces and resting upon the frame surface comprising the bottom of said recess; a balance tape depending from each balance laterally of said fixed sash 75

and attached to said lower sash; and means detachably fastened to said vertical members for concealing said balance tapes and supporting said balances consisting of facing strips contacting said balances.

4. A window construction having a fixed upper sash and vertically slideable lower sash comprising a formed main frame with horizontal and vertical members; a vertically slideable lower sash; vertical side members of said main frame having recesses in each member thereof adjacent to and extending behind the frame surfaces thereof supporting the glass in the fixed upper sash, below the upper horizontal frame member and above said slideable lower sash, adapted to receive and support a spring balance in each of said recesses; a spring balance disposed in each recess abutting against the adjacent frame surfaces and resting upon the frame surface comprising the bottom of said recess; a balance tape depending from each balance laterally of said fixed sash and attached to said lower sash; means detachably fastened to said vertical members for concealing said balance tapes and supporting said balances consisting of facing strips contacting said balances; and means detachably fastened to said frame for concealing and further supporting said balances consisting of a cover plate abutting against each balance.

5. A method of balance application in a window frame having a fixed upper sash and vertically slideable lower sash comprising forming a recess in each of the vertical side members of said angularly formed main window frame above the vertically slideable lower sash and adjacent to said lower sash track in said frame, positioning a spring balance in each of said recesses in close contact with the adjacent surfaces of said frame with the tape orifices directly above the said lower sash with which the balance tapes are connected, and supporting and concealing said balances with abutting angular cover plates detachably fastened to said frame.

6. A method of balance application in a window frame having a fixed upper sash and vertically slideable lower sash comprising the removal of a portion of an inner wall of each of the vertical side members of said angularly formed main window frame above the vertically slideable lower sash and adjacent to said lower sash track in said frame, forming a recess in each member adapted to receive and support a spring sash balance by close contact between adjacent surfaces directly above the lower sash and wholly within the perimeter of the said main frame.
